DESIGN FOR A TABLE COOKER

Oscar M. Anderson, New Britain, Conn., assignor
to Landers, Frary & Clark, New Britain, Conn., a corporation of Connecticut

Application March 14, 1936, Serial No. 61,638

Term of patent 14 years

To all whom it may concern:

Be it known that I, Oscar M. Anderson, a subject of the King of Sweden and resident of New Britain, in the county of Hartford, State of Connecticut, have invented a new, original, and ornamental Design for a Table Cooker, of which the following is a specification, reference being had to the accompanying drawing, forming a part hereof.

In the accompanying drawing:—

Fig. 2 is an end view of the cooker.

I claim:

The ornamental design for a table cooker, as shown.

OSCAR M. ANDERSON.
